UNITED STATES PATENT OFFICE.

JOSEPH A. WESLEY, OF CHICAGO, ILLINOIS, ASSIGNOR TO LU-MI-NUS SIGNS, INC., OF CHICAGO, ILLINOIS, A CORPORATION OF ILLINOIS.

DESIGN FOR AN ADVERTISING SIGN.

Application filed December 7, 1927. Serial No. 24,403. Term of patent 7 years.

To all whom it may concern:

Be it known that I, JOSEPH A. WESLEY, a citizen of the United States, residing at Chicago, in the county of Cook and State of Illinois, have invented a new, original, and ornamental Design for Advertising Signs, of which the following is a specification, reference being had to the accompanying drawing, forming part thereof.

I claim:

The ornamental design for an advertising sign, as shown.

JOSEPH A. WESLEY.
